UNITED STATES PATENT OFFICE.

ELLEN BODLEY CRUMP, OF NITTA YUMA, MISSISSIPPI.

MANICURING DEVICE.

Application filed September 25, 1924. Serial No. 739,886.

This invention relates to a combination implement. It has for its object the provision of an improved article of manufacture adapted to be used for a variety of common needs.

More particularly the improved implement of my invention comprises a variety of novel and useful interchangeable combinations of a handle, cuticle pusher, screwdriver, an abrasive or filing surface, measuring devices, cutting edges, straight edge ruler, etc.

In a preferred practice of my invention, I make use of a flat piece of flexible but relatively thin steel of appropriate length of such design and structure as to embody the combination of features adapted to be used for such purposes as are above indicated. While I prefer to use steel, there is no reason why some other suitable metal or material, either alone or in combination, could not be used. For example, the desired cutting or hard edges could be provided by the use of metal insets and the like. Moreover, the implement may be rigid instead of flexible.

My invention will be better understood by reference to the accompanying drawings, taken in conjunction with the following description, in which:

Fig. 1 is a plan view;

Fig. 2 is an elevational view showing an abrasive edge;

Fig. 3 is a bottom view of Fig. 1;

Fig. 4 is an enlarged transverse sectional view on the line 4—4 of Fig. 1; showing one form of single-taper straight edge;

Fig. 5 is an enlarged transverse sectional view on the line 4—4 of Fig. 1 showing one form of double-taper straight edge;

Fig. 6 is an enlarged transverse sectional view on the line 6—6 of Fig. 1 showing rounded edges on the handle portion;

Fig. 7 is a plan view of a modified handle portion; and

Fig. 8 is a plan view of another modified handle portion.

The implement 10, preferably of flexible steel, although it may be rigid, of appropriate length, say 5" to 8" more or less, is provided with a handle portion 11 of approximately $\frac{1}{2}$ " to $\frac{3}{4}$ " in width with rounded side edges 12. The implement tapers throughout its full length from the handle portion 11 to the point 13.

The top and bottom of the implement are

provided with an abrasive or filing surface 14. If desired such abrasive surface may be placed on only one side; this is optional.

The edge 15 running the full length of the implement is straight so that it may be used as a straight edge ruler. Measuring marks 16, as inches and the fractional divisions thereof, may be suitably marked adjacent to the straight edge portion on either or both the top or bottom of the implement. I have shown these measuring marks as running parallel to the abrasive or filing surface. However, there is no reason why the measuring marks may not be conveniently placed on the handle portion as well.

The straight edge 15 may have its edges 17 beveled or unbeveled as desired. If the steel body is extremely thin, this edge would be sufficiently sharp to provide a cutting edge, such as required for letter-opening. However, I prefer to have this edge beveled either 18 as a single-taper 17 as shown in Fig. 4, or as a double-taper 18 as shown in Fig. 5.

The portion of the straight edge 15, lying between the extreme end or point 13, leading back to the measuring marks 16 for a distance of about 1", is sharpened down to a semi-keen edge 19. The opposite edge 20 of this same portion is appropriately rounded as shown, so as to run from the point 13 to the beginning of the abrasive portion 14 21 for about a distance of 1". This edge is likewise sharpened, preferably to a keen edge.

The edge 21, running adjacent to the abrasive surface 14, is provided with an abrasive or filing surface. This narrow abrasive surface is preferably concaved as shown, so that it may fit over and about the top edge of the finger nails.

The extreme end of the handle portion 11 is preferably rounded and its edge 22 is beveled so as to provide a suitable edge for cuticle pushing purposes. It is desired that this edge not be beveled too sharply so that the edge may be semi-dull to prevent cutting into the skin of the finger. This beveled edge may also be used as a screwdriver in an emergency.

A hole 23 of appropriate design may be placed in the handle portion for the purpose of hanging up the implement. Such a hole may be of such design as to add to the pleasing appearance of the implement. In

Figs. 7 and 8, I have indicated modified forms of handle portions that might be used. The first is a plain rounded handle 24, and the second has an extreme end portion cut in clover-leaf fashion 25. In either instance the end edges are preferably beveled so as to provide for a suitable cuticle pusher or screwdriver.

The following are some of the uses to which my combination implement is particularly applicable:

The straight edge 15 may be used for a letter-opener or for tearing paper and textiles generally. For example, the implement could be placed down upon a sheet of paper or cloth and held in that position with one hand as the other hand is used to pull the paper or cloth along the cutting edge, when the material will part evenly.

The point 13 is particularly adapted for opening knots or strings, and wrappings may be opened by inserting this point and pulling outward. This point may also be used as a finger nail cleaner.

The edge 20, if brought to a keen point, may be appropriately used as an ink eraser, or indeed for any kind of cutting generally done by sharp edges. However, I prefer not

to bring this edge to such a point of keenness as to make it dangerous in handling. 30

The abrasive or filing surfaces 14 and 21 are particularly designed for finger nail filing, although they may be used for any kind of fine filing within their capacity. The beveled edge 22 on the handle portion is 35 adapted to be used as a cuticle pusher or screwdriver, as pointed out above.

The measuring marks 16, in graduations of inches and fractions thereof, may be used 40 as a substitute for a foot ruler.

It will thus be seen that I have successfully combined numerous novel features in one implement which is adaptable for many varied and common everyday uses. 45

I claim:

As an article of manufacture a combination implement comprising, a flat flexible body with a comparatively broad handle portion and narrowing down longitudinally to a point formed by the termination of a straight and a tapered thin edge, abrasive areas on said body for nail-filing purposes, and cutting edges for a relatively short distance from said point. 50

ELLEN BODLEY CRUMP.
